UNITED STATES PATENT OFFICE

LAWRENCE E. CONNELLY, OF CLEVELAND, OHIO, ASSIGNOR, BY MESNE ASSIGNMENTS, TO FOSTER WHEELER CORPORATION, OF NEW YORK, N. Y., A CORPORATION OF NEW YORK

STEAM GENERATOR

Application filed November 17, 1924, Serial No. 750,326. Renewed January 6, 1930.

This invention relates to steam generators of the type known as water tube generators, and the object thereof is to provide means to cause an independent circulation of the 5 feed water whereby the same will be raised in temperature before it enters the generator portion of the structure.

I have found by experience, especially at high overloads, that the water lever in the 10 rear or feed-water economizer bank of tubes drops down several feet below their upper ends and the bottom of the steam or rear drum so that the upper part of these tubes becomes 15 dry. This is caused, in part, by the steam bubbles in the water in the other banks of tubes and in the steam liberating drum which causes the water to be lighter therein than the water in the rear drum and economizer or rear bank of tubes, thus allowing the water in said 20 rear bank to fall until a balance of gravity is reached.

My invention is designed to prevent the water level in the rear drum and economizer bank of tubes from falling below the water 25 level in the steam liberating drum, so that the flow of feed water from the rear drum into the circulating system of the generator proper will be constant.

I have also found by experience that there 30 is slightly higher pressure in the steam drum than in the rear drum, which may be as much as a pound difference thereby causing water to flow from the liberating drum into the rear drum, which my invention prevents.

My invention also reduces the temperature 35 of the furnace gas leaving the boiler setting by causing the boiler tubes to absorb more heat by maintaining the economizer tubes full of water and thereby preventing overheating 40 of the same.

The features of my invention are herein-after fully described and pointed out and are illustrated in the accompanying drawings, in 45 which:

Figure 1 is a side elevation of a steam generator according to my invention, with the several drums thereof in section.

Figure 2 is an enlarged sectional view of 50 the rear upper steam drum.

Figure 3 is an enlarged central transverse

section of the lower or mud-drum on the line 3 in Fig. 4, looking in the direction of the arrow.

Figure 4 is a longitudinal vertical section of the same on the line 4 in Fig. 3, looking 55 in the direction of the arrow.

In these drawings A indicates the mud-drum, B indicates the front or water drum, C indicates the steam liberating drum and D indicates the steam and feed-water drum. 60 E indicates a bank of up-flow tubes connecting the mud-drum A and water drum B. F indicates a bank of up-flow tubes connecting the water-drum B and steam liberating drum C. G indicates a bank of water tubes 65 connecting the steam liberating drum C and feed-water and steam drum D below the water level in said drums as indicated by the broken lines c and d in Fig. 1. H indicates a bank of steam conveying tubes connecting 70 the upper portions of the steam liberating drum C and feed-water and steam drum D, through which steam flows from the liberating drum C into the feed-water drum D. D' indicates the steam main connection through 75 which steam is taken from the drum D for use.

J indicates a bank of down flow water tubes connecting the liberating drum C and mud-drum A. K indicates a series of down-flow water tubes connecting the feed-water drum D and mud-drum A. 80

The feed water and steam drum D is provided with a feed-water intake connection L from which a feed water connecting pipe L', 85 see Fig. 2, extends over the open upper side of a feed-water receiving trough L² within said drum D, said trough extending longitudinally of said drum, a substantial portion of the length thereof. Within said drum D a vertical wall plate L³ is secured to the shell of said drum, and extends upwardly therefrom to the water level d therein, as shown in Fig. 2, the trough L² being on the right hand side of said plate L³. The plate L³ being permanently secured to the shell by the angle L⁴ and heads of the drum D by angles L⁵ prevents water from one side of 90 said plate flowing to the opposite side thereof, except over the upper edge thereof. 95

Down-flow feed-water tubes M lead from the portion of the feed water drum D at the right hand side of the plate L³ to the mud-drum A, and up-flow feed-water tubes N are connected with said mud-drum A and feed-water drum D at the left hand side of said plate L³.

Within the mud-drum A, a chamber P is permanently secured to the shell thereof, the ends of said chamber being closed, as shown in Figs. 3 and 4, so that feed-water therein will not flow from said chamber into the rest of the drum, said chamber P, enclosing the lower ends of the down-flow and up-flow feed water tubes M and N causes the feed-water to flow downwardly from the right hand side of the vertical partition plate L³ in the drum D, into the chamber P in the mud-drum A and thence upwardly into the feed-water and steam drum D at the left hand side of said partition plate L³, from where it is conducted into the boiler proper, by the series of down-flow tubes K, which connect said feed-water and steam drum D and mud-drum A, from whence it continues in endless circulation through the drums and banks of tubes A, E, B, F, C and J, while steam liberated therefrom in the drum C, passes through the bank of tubes H into the drum D, from which it is taken through the connection D'.

The chamber P, see Figs. 3 and 4, consists of an upper longitudinal plate P' permanent-ly secured to the shell of the mud-drum A to which a co-extensive side plate P² is re-movably secured by means of bolts and nuts p. At the lower edge of said chamber an angle-iron is permanently secured to the shell of the drum A, to which the lower plate P³ is secured by means of bolts and nuts p'. The upper edge of the plate p³ is secured to the lower edge of the plate P² by means of bolts and nuts p², while the ends of said chamber are closed by end plates, P⁴ which are secured in place by means of bolts and nuts p³.

Within the chamber P is placed a longitudinal pipe Q which is provided with a series of openings q through the wall there-of, and said pipe is intermediately connected with a blow-off pipe R which extends through the lower plate P³ of the chamber R' of the drum A. This blow-off apparatus Q and R is secured to the lower plate P³ of the chamber P, so that, when desired the plates P² and P³ can be removed by removing the bolts and nuts, p, p', p² and p³, said blow-off apparatus will be removed with the lower plate P³. The several walls of the chamber P are so secured together, and to the shell of the mud-drum A as to effectually prevent any circulation of water between the interiors of said chamber P and mud-drum A, said chamber only serving as a header for the lower ends of the down-flow feed-water tubes M and up-flow feed-water tubes N.

In Fig. 1, I show a preferred arrangement of baffle-walls, S, T, U and V, the line W indicating the rear wall of the boiler setting, the curved arrows indicating the course of the furnace gas, which leaves the setting 70 through the space between the baffle-wall V and the rear wall W.

In this figure it will be noted that the up-flow feed-water tubes N are directly exposed to the hot down-flow furnace gas during the 75 final pass thereof, while the down-flow feed-water tubes M are only indirectly exposed to the furnace gas, being shielded therefrom by the tubes N.

In operation the feed-water is introduced 80 by the supply pipe L' into the trough L² which distributes the same evenly throughout the length of the drum D at the right-hand side of the partition plate L³, from which it flows downwardly through the tubes M into 85 the chamber P, absorbing the indirect heat of the fire gas, the difference between the tem-perature of the combustion gases and the down-flowing feed-water in the tubes M being such that a transference of heat to the wa-ter will be effective. Then the upflowing, par-tially heated water from the chamber P flows through the tubes N, which are directly ex-posed to the down flowing fire gas, the per-centage of difference in temperature between 90 the upflowing water and the fire gas will be sufficient to continue the transference of heat thereto, so that the the feed water when it re-enters the drum D at the left hand side of the partition plate L³ is ready to commence 100 boiling.

From the steam and feed-water drum D down-flow feed-water tubes K lead from the left-hand side of the partition plate L³ to the mud-drum A, through which heated feed-105 water flows into the boiler proper.

The down and up flow of feed-water in the economizer tubes M and N effectually prevents the upper portions of said tubes go-ing dry by reason of the difference in the 110 gravity of the relatively cool-feed-water therein, and the boiling water in the boiler tubes E, F and J and the drums B and C, so that the water level in said drums will be sub-stantially the same, except for the surface agi-tation of the water in the liberating drum C, 115 due the liberation of steam therefrom, so that any flow of water through tubes G back-wardly from the drum C to the drum D is el-liminated. With the construction herebe-120 fore described, it is entirely optional with the boiler maker whether the tubes G are used, as they form no part of this invention,

Having thus fully shown and described 125 suitable apparatus for embodying my inven-tion and the operation of the same so that others can utilize the same, what I claim as new and desire to secure by letters patent is:

1. In a steam generator, a mud-drum, a water drum above and in front of said mud-130

drum, a bank of up-flow water tubes connecting said mud-drum and water-drum, a steam liberating drum above and to the rear of said water drum, up-flow water tubes connecting
5 said water drum and steam liberating drum, a bank of down-flow water tubes connecting said steam liberating drum and mud-drum, a steam and feed water receiving drum at the rear of said steam liberating drum, a bank of
10 steam conveying tubes connecting the upper portions of said steam liberating drum and feed-water receiving drum, down-flow and up-flow feed-water tubes connecting said feed-water drum and mud-drum, a water-
15 tight chamber secured to the shell of and within said mud-drum enclosing the lower ends of said down-flow and up-flow feed-water tubes, a vertical water-tight division plate secured to the lower portion of the shell
20 of said feed-water drum between said down-flow and up-flow feed-water tubes, means to supply feed-water to the down-flow side to said plate, and a series of down-flow tubes connecting said feed-water drum
25 adjacent to said up-flow feed-water tubes and said mud-drum outside of said chamber.

2. In a steam generator, a mud-drum, a feed-water receiving drum, a steam liberating drum, down-flow water tubes connecting
30 said mud-drum and steam liberating drum, a series of down-flow feed-water tubes connecting said feed-water drum and said mud-drum, up-flow feed-water tubes connecting said mud-drum and feed-water drum, a
35 water-tight chamber within said mud-drum enclosing the lower ends of said down and up flow feed-water tubes, a fire baffle wall behind the down flow water-tubes connecting the steam liberating and mud-drums, and a
40 fire baffle wall extending from the feed-water drum downwardly behind the down-flow feed-water tubes, whereby the furnace gas is caused to flow downwardly among said down and up-flow feed-water tubes.

45 3. A boiler comprising in combination a separating and a water drum interconnected by steam and water conduits, the water conduits being connected to the bottom portions of the drums and the steam conduits being
50 connected to the top portions of the drums, and said water drum having a feed water inlet and a steam outlet, a circulating drum entirely disposed below the normal water level of the boiler and connected to said separating
55 drum by a bank of water circulating conduits, and a downwardly located mud drum inter-connected with each of the said drums by means of a single bank of water circulating conduits, the bank of conduits from the
60 mud to water drum having less sectional area than each of the other banks, said other banks having substantially equal areas.

In testimony whereof I affix my signature.
